METHOD OF AND APPARATUS FOR
EFFECTING TIGHT COUPLINGS

Chester K. Brooks, Kirtland Hills, and Ernest H. Schmidt, Cleveland Heights, Ohio, assignors to National Malleable and Steel Castings Company, Cleveland, Ohio, a corporation of Ohio

Application April 16, 1929. Serial No. 355,456

3 Claims. (Cl. 213—223)

This invention has for its chief object the provision of means for eliminating slack in railway draft attachments, so that cars may be tightly coupled together and the ensuing advantages of smoothness in stopping and starting and improvement in riding qualities obtained. A further object is to provide means which is not only adapted to take up the slack between cars but which also does not interfere with the operations of coupling and uncoupling. In carrying out our invention, we make use of the buffers which act to hold the vestibule platforms of adjacent cars in contact; and in this connection we provide means for augmenting the power or capacity of said buffers so that they may hold the cars apart and thereby obviate slack in the couplers and draft attachments. In addition, we provide means for reducing said increased capacity when coupling or uncoupling is to be effected. An additional feature of our invention resides in the provision of means simple in construction and readily applicable to existing equipment for accomplishing the results above outlined. Other features of the invention will be hereinafter described and claimed.

In the accompanying drawings:

Fig. 1 is a plan view partly in section of a buffer embodying our invention, the train pipe and valve connections cooperating with the buffer being indicated diagrammatically and a portion of the associated car structure being shown in dot-dash lines.

Fig. 2 is a longitudinal vertical sectional view on line 2—2 of Fig. 1;

Fig. 3 is a transverse vertical section on line 3—3 of Fig. 2;

Fig. 4 is a transverse vertical section on line 4—4 of Fig. 2, and

Fig. 5 is a sectional view of a detail.

In the drawings the platform deck casting of a car is indicated in dot-dash lines at 5, the center stem of the vestibule platform buffer at 6, and the side buffer stems at 7. The platform deck casting is shown broken away at one side for the sake of clearness, and likewise one of the buffer stems 7 is shown fragmentarily. The buffer plate is indicated diagrammatically at 8 and its face line at 8'. The associated coupler is not shown but the position of the pulling face 50 of the coupler knuckle is diagrammatically indicated at 9. 10 designates one of the side buffer springs with which the side stems 7 are provided. As shown, said spring surrounds a rearwardly extending portion 11 of the associated stem 7, said portion 11 being of reduced diameter. A

washer 12 is seated against shouldered portion 13 of the stem and is provided with an inner extension 14 which assists in maintaining the spring centered with respect to the stem. A similar washer 15 having an extension 16 may 60 rest against member 17 of the platform deck casting. A nut 18 threaded on the end of portion 11 of the stem 7 normally bears against a boss 19 on said casting member 17. It will be understood that the stem 7 connected to the 65 other side of the buffer plate 8, and shown fragmentarily in Fig. 1, is of the same construction and is acted upon by a spring in the same way as the stem 7 above specifically described.

The buffer comprises a friction case 20 in 70 which are mounted friction shoes 21, 21 adapted to be pressed outwardly against said case by a wedge 22 upon inward movement of the central stem 6. Inward movement of said shoes is resisted by a spring seat 23 and a light spring 24. 75

When the cars are brought together for coupling the plate 8 is moved inwardly a certain distance and the stems 6 and 7 and wedge 22 moved accordingly, before the couplers are interlocked. This movement is in practice about 80 three inches, and the resistance offered by the buffer is simply that of the side springs 10, the center spring 24, and the very slight friction developed by the shoes 21 against the casing 20, set up by the compression of the light spring 24. 85

We have provided means whereby the action of the buffers may be sufficiently increased to hold the cars apart and thereby obviate slack in the coupler and draft attachments and maintain the couplers in tight pulling contact with each other. 90 This means may be constructed substantially as follows:

Secured to the friction case 20 by cap screws 25 is a casing comprising two air cylinders in 95 which are mounted pistons 27. Each piston consists of a piston head 28, a leather washer 29, and a metal washer 30, and is secured to the associated piston rod 31 by a nut 32. Each of the piston rods 31 is in turn secured to the spring seat 23 by a vertical pin 33. The inner ends of 100 the cylinders 26 communicate through pipe connections 34 with a pipe line 35 which in turn communicates through pipe 36 with the usual air reservoir carried by the car. The piping 35 may be placed in communication with the pipe 36 105 or vented to the atmosphere by means of a three way valve 37. The latter, as illustrated in Fig. 5, is rotatable in casing 38 and is provided with ports 39, 40, and 41. For operating the valve the handle 42 thereof is shown connected through 110

reach rod 43 to arm 44 of the usual angle cock handle 45 of the train pipe line 46.

While but one of the vestibule platform buffers has been specifically described and illustrated, it 5 will be understood that we contemplate that each of the vestibule platform buffers on each car be constructed similarly to that above described. As will be apparent, each of the buffers may be connected to the air reservoir on its car 10 or placed into communication with the atmosphere by connections which are duplicates of those described hereinbefore. It will be understood that two train pipe angle cocks and corresponding control handles (similar to angle cock 15 47 and handle 45) are provided on each car, one at each end thereof, and it will be evident that each of the vestibule platform buffers on the car may be controlled through a three-way valve operated by the adjacent angle cock handle 20 in the same way as has been outlined in connection with the buffer and connections herein specifically illustrated.

In operation, when the cars are brought together and the couplers interengaged, the buffer plate 8 and buffer connections have been moved inwardly as hereinbefore noted; and the pistons 25 27 have been correspondingly moved from the full to the dotted line position shown in Fig. 1. After the coupling is made, including the coupling 30 of the usual air and steam line, the switchman goes through the customary procedure of opening the angle cock 47 by moving its handle 45 from A to B. Through the arm 44, rod 43, and arm 42 the three-way valve 37 is operated so as 35 to place the ports 39 and 40 in communication with pipes 35 and 36 (as shown in Fig. 5), thereby bringing the pipes 34, 34, into communication with the air reservoir carried by the car. Air now flows from said reservoir through valve 37 40 and associated piping into the cylinders 26, acting upon the pistons 27 and thereby pressing forwardly on the buffer plate 8. The buffer plate on the adjacent or preceding car with which said plate 8 contacts is also acted upon by its buffer 45 mechanism, the power of which is increased by turning of the associated train pipe angle cock handle on said preceding car. Upon admitting air into the cylinders 26, the force applied to the pistons 27, and through them to buffer plate 8, 50 results, in cooperation with the buffer of the preceding car, in holding the buffers together with increased pressure.

Now as soon as the train starts to move, the 55 coupler knuckles come into pulling engagement with one another; any slack in the draft attachments is pulled out and the draft gears are compressed a certain amount in draft. In other words, the adjacent cars move apart from each other the amount allowed by coupler slack, draft 60 attachment slack, and by the resulting draft gear compression. Because of the air pressure behind the pistons 28 and the compression of the spring 24, as well as the side springs 10, the buffer faces 8' remain in tight contact, the pistons moving from their dotted-line position toward the position shown in full line. This allows more air under pressure to enter the cylinders.

If a surge occurs in the train while under way, due to shutting off steam, brake application or 70 any other cause which would normally tend to result in a run-in of slack, (which is the chief cause of rough riding in passenger equipment), this surge is immediately resisted by a high frictional resistance set up by the wedging system 75 of the buffer comprising the wedge 22, friction

shoes 21 and spring seat 23, to the latter of which the piston pressure is exerted. This frictional resistance is sufficient to maintain the coupler knuckles in pulling position and the draft gears in their partially compressed position and thus 80 prevents the objectionable running-in of slack.

It will be seen that the further the draft gears are compressed in pulling, the further forward the pistons will be in their cylinders and, consequently, the greater the travel of these pistons 85 and the buffer friction mechanism will be when any surge occurs which tends to allow the draft gears to return to their normal position. The cars toward the head end of the train are normally subjected to greater draft action because of 90 their nearness to the locomotive; also, on sudden brake application the resulting surge is greater toward the head end of the train. This pneumatic buffer is automatically able to take care of this heavier surge action at the head end of 95 the train because its pistons at that time will be near the forward end of the cylinders and there consequently will be a greater available amount of travel in the pneumatic and friction mechanism with which to resist or absorb the resulting 100 surge. The travel of the pistons in the cylinders is so adjusted that when the draft gears are pulled solid the pistons are at the forward end of their stroke, as shown in Fig. 1, and likewise when the draft gears are buffed solid the pistons are at 105 the inner end of their stroke.

A check valve 48 may be provided for the purpose of preventing the air in the buffer cylinders 26 from flowing back into the reservoir; the building up of excessive pressure in said reservoir 110 by the pneumatic section of the buffer being thus precluded. The air which is trapped in the cylinders and adjacent piping will be compressed by the aforesaid inward movement of the piston and additional piston resistance will thereby be 115 built up.

When it is desired to uncouple a car from the train the switchman first closes the angle cock 47 on said car, moving the handle from B back to its original position indicated at A, which moves 120 the three way valve handle 42 from C to D; thereby shifting a solid portion of the three way valve 37 opposite pipe 36, placing port 41 in communication with pipe 35, and bringing port 40 opposite opening 38a in the casing 38. The valve is now 125 closed to pipe 36 and the connected air reservoir of the car, while the piping 35 is opened to the atmosphere thus permitting the air in the pneumatic buffer system to exhaust so that its pressure will be reduced to that of the atmosphere. 130 The switchman next uncouples the various hose connections and puts the coupler in lock set position ready to pull away.

It will be noted that the mechanism which we have provided is readily applicable to existing 135 passenger car equipment and requires no change other than drilling a few holes and adding the piping and valves for operating the device. The buffer is shown bolted to the car at 49, 50, and 51 and may be assembled as a unit before application of the car. It may be noted that the buffer spring 24 serves the two functions of developing 140 spring and frictional resistance and releasing the pistons or holding them in a forward position.

It will be seen that the process of coupling and 145 uncoupling the cars and their train lines is exactly the same as with the ordinary equipment in which the conventional spring or friction buffer is used, the act of opening and closing the angle cock automatically bringing the pneumatic buff- 150

er into or out of action. The resistance of the spring 24 is so light that it offers no substantial resistance to the coupling up of the cars as its main purpose is merely to bring the pistons to the forward end of their stroke when cars are uncoupled.

If desired, a safety valve may be installed in the piping between the three way valve and the cylinders in order to prevent building up of pressure above a predetermined amount. The application of such valve being obvious, it is believed unnecessary to show the same in the drawings.

The terms and expressions which we have employed are used as terms of description and not of limitation, and we have no intention, in the use of such terms and expressions, of excluding any mechanical equivalents of the features shown and described or portions thereof, but recognize that various structural modifications are possible within the scope of the invention claimed.

What we claim is:

1. In combination, a vestibule platform buffer including friction elements, a spring acting at all times upon certain of said elements to press said

elements into frictional contact, means for transmitting fluid pressure to said friction elements to increase the frictional resistance thereof, and means to control the operation of said means.

2. In combination, a vestibule platform buffer, friction means operatively connected with said buffer, means for transmitting fluid pressure to the first-named means to increase the frictional resistance thereof, and means to control the operation of the second-named means.

3. In a device for taking up slack in coupler and draft gear parts between cars, a buffer member, friction generating means operatively connected therewith, means for transmitting fluid pressure to said friction means for increasing the frictional resistance thereof, a train pipe line, means to supply air pressure to said line, valve means to control the flow of pressure through said line, means for operating the valve, and means operatively connected with said valve operating means and operable therewith for admitting pressure to said transmitting means.
